BELT-ATTACHED PURSE

William F. Woolfolk, 3535 Lincoln Ave.,
Altadena, Calif. 91001

Original design application Apr. 15, 1968, Ser. No. 11,456, now Patent No. 214,984, dated Aug. 19, 1969. Divided and this application Mar. 10, 1969, Ser. No. 16,146

Term of patent 14 years

Int. Cl. D2—08

U.S. Cl. D2—400

FIG. 1 is a front view of a belt-attached purse, showing my new design;

FIG. 2 is a side view thereof as seen from the right side of FIG. 1;

FIG. 3 is a rear perspective view thereof, showing the right side of FIG. 1; and

FIG. 4 is a side view thereof as seen from the left side of FIG. 1.

The bottom of the belt-attached purse is substantially plain and unornamental.

This is a division of design application Ser. No. 11,456, filed Apr. 15, 1968, for "Belt Attached Purse" and now Pat. No. D. 214,984.

I claim:

The ornamental design for a belt-attached purse, as shown and described.
